UNITED STATES PATENT OFFICE.

JOHN FINN, JR., OF MILL VALLEY, CALIFORNIA, ASSIGNOR TO PAUL LAU, OF SAN FRANCISCO, CALIFORNIA.

DESIGN FOR A CANDLE.

Application filed May 2, 1925. Serial No. 13,287. Term of patent 3½ years.

To all whom it may concern:

Be it known that I, JOHN FINN, Jr., a citizen of the United States, residing in Mill Valley, Marin County, and State of California, have invented a new, original, and ornamental Design for a Candle, of which the following is a specification, reference being had to accompanying drawing, forming part thereof, wherein—

Fig. 1 is a side elevation, and
Fig. 2 is a plan view.

I claim:
The ornamental design for a candle, as shown.

JOHN FINN, JR.
